LAMP AND REFLECTOR THEREFOR.

1,175,420.

Specification of Letters Patent.

Patented Mar. 14, 1916.

Application filed June 14, 1915. Serial No. 33,910.

To all whom it may concern:

Be it known that we, CARRIE SWOPE FORD and SAMUEL H. BAKER, both citizens of the United States, residing, respectively, at Oakland, county of Alameda, and State of California, and Pasadena, county of Los Angeles, State of California, have jointly invented new and useful Improvements in Lamps and Reflectors Therefor, of which

10 the following is a specification.

This invention relates to lamps and reflectors therefor, and it has for its object to provide a lamp or reflector which will project only diffused light rays and project such diffused rays evenly throughout the zone to be illuminated, and avoid the focusing in certain spots of any of the light rays.

Lamp reflectors as ordinarily constructed are so designed as to provide a focus for the 20 light-rays, and the light projected from such standard reflectors or lamps provided with the same is, in many instances, objectionable and for certain uses highly undesirable, as for instance, in headlights for automobiles 25 and other vehicles, where the use of high power lights is desirable, but the glare of the light temporarily blinds persons facing the same, and results in many casualties, as when the drivers of meeting vehicles are 30 suddenly confronted by powerful headlights such as are usually employed on automobiles and the like; with lamps or reflectors organized in accordance with the invention, this trouble is entirely eliminated, as the 35 diffused light emitted does not have the blinding effect upon a person facing the same, no part of the reflector tending to bring the rays to a sharp focus. Lamps or reflectors organized in accordance with the 40 invention may be employed wherever any artificial light is needed for either interior or exterior illumination, the zone of ray projection being forward of the reflector and such zone extending in every direction 45 forward of the plane of the extreme forward portion of the reflector, this distribution rendering lamps provided with the hereinafter described reflector adaptable for service as street lamps as well as for vehicle 50 headlights and many other purposes.

With the above and other objects in view, including relative simplicity and inexpensiveness in construction, length of life or durability and general efficiency, the invention consists in the novel and useful provi-

sion, construction, formation, combination, association and relative arrangement of parts, members and features, all as herein-after described, shown in the drawing and finally pointed out in claims.

In the drawing: Figure 1 is a front elevation of a lamp organized in accordance with the invention; Fig. 2 is a side elevation of the same; Fig. 3 is a central horizontal sectional view taken upon the line x^2-x^3 , 60 Fig. 1, and looking in the direction of the appended arrows, this view showing the reflector, lamp casing and glass front in section; Fig. 4 is a central vertical sectional view through the reflector, lamp casing and glass front, the view being taken upon the line x^4-x^5 , Fig. 1, and looking in the direction of the appended arrows; and Fig. 5 is a fragmentary plan view of an automobile provided with a pair of lamps organized in accordance with the invention, 75 and so mounted as to properly illuminate the roadway or course taken by an automobile.

Corresponding parts in all the figures are 80 designated by the same reference characters.

Referring with particularity to the drawing, in the embodiment of the invention therein shown, A designates a headlight organized to embody the invention, B designates a reflector therefor, C designates illuminating means, and D designates supporting means for such headlight.

In the form of the invention shown in the drawing, the headlight A comprises in addition to the reflector B and illuminating means C, a casing a provided with a rim b hinged as at c to the casing a , and a front glass d mounted in the rim b , and forming, together with the casing a , a weatherproof 95 housing for the reflector and illuminating means with other attendant features.

The reflector B comprises a concave body of suitable material which may be of polished metal, silvered glass, or any other 100 suitable reflecting material, such reflector B resembling in general contour, the human eye, the periphery or forward lip e of the reflector preferably being formed and curved identically as are the upper and 105 lower eyelids of the human eye, this formation making it possible to insure a wide angle distribution of the light rays emitted, the zone into which the rays are projected being included in the wide angle, which 110

angle is approximately 180 degrees. The wide angle distribution of light rays takes place in every direction forward of a plane in which the reflector periphery is in part located. The forward lip 6 or periphery of the reflector is arranged in a vertically disposed substantially cylindrical surface which, in the present instance, has its center of curvature at the rear of the lamp. The 10 lip 6 is preferably rounded as at 6^a, Fig. 4, and the reflector is so formed that no focusing of the light rays at any point will occur, particular attention being given in the formation of the reflector to the part 6^b immediately behind the illuminating means C, so that no rearwardly ranging rays from such illuminating means could be projected straight ahead from such portion 6^b of the reflector B. Assuming that the lamp is in 20 the position shown in the drawing, the side peripheral portions 6^c and 6^d are rearward of the overhanging upper and lower peripheral lip portions 6^e and 6^f due to the eyelid-like formation of the reflector. The 25 peripheral lip portion 6^a of the reflector is formed with a slightly different curve than the peripheral lip portion 6^c.

The illuminating means C is shown as in electric light 7, the glass bulb 8 of which is 30 preferably of elliptical formation at its forward portion 8^a, such forward portion 8^a being positioned centrally of the reflector and approximately in line with the upper and lower peripheral lips 6^c and 6^d thereof. 35 The glass bulb 8 of the electric light is preferably heavily frosted or otherwise darkened, as at 8^b, this frosted surface extending forwardly from the base 8^c of the lamp to such point as is necessary to shut off or 40 dim the rearwardly ranging rays of the light, thus assisting in preventing the aforementioned objectionable focusing of the light rays. The lamp bulb 8 is lightly frosted or otherwise shaded, as at 8^d at its 45 forward portion, such shading 8^d covering only enough surface to shut off the direct forward rays of the filament or other light producing portion 8^e of the lamp.

The support D preferably comprises a 50 bifurcated bracket 9 between the furcations 9^a and 9^b of which the lamp is supported, as by means of bosses 9^c provided on the lamp casing, such bracket serving as a convenient means of securing the lamp to a 55 vehicle.

A conventional latch 10 is provided to 60 properly secure the glass front d and its rim b in closed position against the casing a, it being understood that such glass supporting rim b and the complementarily formed casing edge 11 conform as nearly as possible to the eyelid-like periphery of the reflector, so as not to in any way interfere with the projection of light rays from such 65 reflector.

In Fig. 5 is illustrated the preferred manner of employing a pair of lamps organized to embody the invention when such lamps are to be used as automobile headlights. As hereinbefore stated, the peripheral lip at one side edge 70 of the reflector differs in curvature from the peripheral lip at the other side edge of the reflector, conforming in this respect to the formation or arrangement of the eyelids of the human eye, and when the lamps are to be used 75 as shown in Fig. 5, the lamps are arranged so that the side peripheral lip having the greater curvature is outwardly disposed with respect to the longitudinal axis of the automobile, and furthermore, the lamps may be 80 faced slightly outward so as to thoroughly light up the sides of the road as well as the road immediately ahead of the automobile; even were the lamps not faced slightly outward, the wide angle light distribution, 85 namely, 180 degrees, would insure the lighting up of the road or track in making turns, in advance of the turning of the vehicle, thus avoiding the confusion of both 90 proceeding and advancee; when the lamps are 95 to be used as just described, the reflectors and lamps may be almost identical except in that they are made in "rights and lefts" which presents no difficulties of manufacture, as one reflector is simply reversed as to the 100 position of its greater curved end, this allowing the reflectors of both lamps of the pair to be made by means of the same form or forms. When reflectors or lamps embodying the invention are used for such 105 purposes as street or interior lighting, it is not so important that one side peripheral lip of the lamp be of greater curvature or extension than the other side peripheral lip.

The operation, method of use and advantages of the improvements in lamps or reflectors constituting the invention will be readily understood from the foregoing description taken in connection with the accompanying drawing and the following 110 statement. The light rays from the lamp, which is placed well forward in the reflector, strike the reflector in such manner that focusing of rays is impossible, the frosted or shaded rearward portion of the lamp bulb 115 preventing any strong light rays from striking the reflector and being reflected "straight ahead" or focused, and the general contour of the reflector insures the diffusion and scattering of all rays projected 120 therefrom, this resulting in an even flood of light covering, as before stated, a wide angle field, all portions of such field equidistant from the reflector being equally illuminated.

Having thus disclosed our invention, what 125 we claim and desire to secure by Letters Patent is:

1. The combination of a reflector with a source of light arranged substantially at the focus thereof, said reflector having an 130

aperture with sides curved substantially as are the lids of the human eye, the curve of a horizontal section through the reflector being constantly variable so that the field of the projected light within a radius of substantially 170° is of practically uniform intensity.

2. The combination of a reflector with a source of light arranged substantially at the focus thereof, said reflector having an aperture elongated laterally in opposite directions and the edges of which are arranged in a vertically disposed substantially cylindrical surface, the curve of a horizontal section through the reflector being constantly variable so that the field of the projected light within a radius of substantially 170° is of practically uniform intensity.

3. The combination of a reflector with a source of light arranged substantially at the focus thereof, said reflector having an

aperture elongated laterally in opposite directions and formed with edges arranged in a vertically disposed substantially cylindrical surface, the curve of a horizontal section through the reflector being constantly variable so that the field of the projected light within a radius of substantially 170° is of practically uniform intensity, and the curvature of a vertical section through the reflector being also constantly variable to produce a substantially uniform field of practically the same intensity for a much restricted vertical radius.

In testimony whereof, we have signed our names to this specification in the presence of two subscribing witnesses.

CARRIE SWOPE FORD.
SAMUEL H. BAKER.
